UNITED STATES PATENT OFFICE.

CHARLES O. PELLETIER, OF OAKLAND, CALIFORNIA.

DEVICE FOR MOVING DISAPPEARING BEDS.

1,067,621.

Specification of Letters Patent. Patented July 15, 1913.

Application filed November 7, 1912. Serial No. 729,986.

To all whom it may concern:

Be it known that I, CHARLES O. PELLETIER, a citizen of the United States, residing at Oakland, in the county of Alameda and State of California, have invented new and useful Improvements in Devices for Moving Disappearing Beds, of which the following is a specification.

The present invention relates to that class of disappearing beds in which the bed is received within a closet having an ordinary closet door, the bed being generally of greater width than the door, and the bed and door swinging independently on vertical 15 hinges, either in vertical alinement with each other or as nearly so as practicable.

The object of the present invention is to provide means whereby, as desired, the bed may be swung outward with the door, or 20 the door may be swung outward without any corresponding movement of the bed.

In the accompanying drawing, Figure 1 is a front view of a closet having a bed of the character described therein, the door being broken away in part; Fig. 2 is a horizontal sectional view on the line 2—2 of Fig. 1; Fig. 3 is an elevation of an edge of the bed, looking in the direction of the arrow in Fig. 2, showing a latching bar in its normal position in full lines and in other positions 30 in dotted lines.

Referring to the drawing, 1 indicates a closet wall, 2 the door thereof, hinged, as shown at 3, to the door casing 4. Secured 35 by screws 5 to the floor 6 of the closet, immediately behind the door and close to its hinged side, is an angle iron 7, having a vertical member 8, to which is secured one strap 9 of a hinge, the other strap 10 being secured 40 to the head frame of a collapsible bed 11. Said door is provided with the usual latch 12, and upon the square shank 13 of said latch, between the door plate and the handle on the inner side of the door, is 45 passed a latching bar 14 having at one end a square hole fitting snugly around said shank. Said bar is arranged in said shank so that it extends downward at an angle of about 45° away from the adjacent door casing. On turning the shank in one direction 50 to withdraw the latch, said bar is turned upward through an angle of about 45° to an

approximately horizontal position. In moving into this position it passes into a notch or recess 16 formed in the lower edge of a 55 plate 17 secured to a side of the head frame of the bed nearest said handle, and when the bar is in this position, the bed will swing open with the door. But upon turning the shank of the latch in the other direction to 60 withdraw the latch the bar is moved still farther downward through an angle of about 45° to an approximately vertical position, the bed will not so swing open with said door. Upon releasing the handle, the bar 65 will drop out of engagement with said recess.

I claim:

1. In combination with a door having a latch and a handle for operating said latch, and a bed arranged on a vertical pivot in 70 close proximity to the line about which the door swings, a device secured to said latch and arranged to be moved into engagement with a part of the bed when the latch is moved to open the door.

2. In combination with a door having a latch and a handle for operating said latch, and a bed arranged on a vertical pivot in 80 close proximity to the line about which the door swings, a device secured to said latch and arranged to be moved into engagement with a part of the bed when the latch is moved in one direction to open the door, but not so moved into engagement when the latch is moved in the other direction to open 85 the door.

3. In combination with a swinging door, having a latch, and a collapsible bed having a pivot in close proximity to the line about which the door swings, an operating shank 90 connected with said latch, a bar connected to said shank on the same side of the door as the bed, and a plate secured to the bed and having a recess into which a portion of said bar is adapted to be received when the 95 shank is operated to withdraw the latch.

In testimony whereof I have hereunto set my hand in the presence of two subscribing witnesses.

CHARLES O. PELLETIER.
